Alvin P. Morris

UNITED STATES PATENT OFFICE.

ROBERT L. COONEY, OF ATLANTA, GEORGIA.

THERMIONIC VALVE.

Application filed April 8, 1928. Serial No. 100,701.

This invention relates to thermionic valves and particularly to the construction of the base portion of the same whereby the use of sockets for mounting the valves may be entirely obviated.

One of the objects of the invention is to minimize the number of electrical connections necessary for intercalating the valve in the wiring system with which it is associated.

Another object is to construct the base in such manner as to avoid capacity effects between the terminals.

Still another object of the invention is to provide a base with a non-microphonic portion, the same constituting the sole support for the valve.

Other objects of the invention will appear as the following description of an illustrative embodiment thereof proceeds.

In the drawings:—

Fig. 1 is a side elevation of a thermionic valve embodying the principles of my invention.

Fig. 2 is a section of the same taken along the line 2—2 of Figure 1.

Fig. 3 is a fragmentary view showing the lower end of the base portion partly in section.

Referring now in detail to the several figures, the numeral 1 represents in general an audion tube having the usual electrodes, 1 and 2, 3 and 4 designate the leads or conductors to the electrodes. The tube includes a base portion 5 formed from suitable insulating material such as a phenolic condensation product. Terminals 6, 7, 8 and 9 are embedded in the material of the base, or pass through it otherwise in any suitable manner, said terminals being angularly diverted within the base, so as to emerge laterally therefrom as shown, and preferably in radial directions.

One of the characteristics of the terminals is that they are continuous throughout, being free from frictional contacts or other mechanical joints, so that the resistance within said terminals is kept low and there are no microphonic contacts to interfere with the performance of the tube. The terminals are preferably provided with connectors 10 to which the appropriate leads of the wiring system may be attached, this being the only mechanical joint necessary to be made, in contradistinction to the numerous serially arranged mechanical and

frictional contacts inherent to all forms of socket mountings.

In order to assure the proper electrical connections being made, one of the connectors, for instance that shown at 13 in Fig. 1 may be made of different shape from the others so as to distinguish it therefrom so that the B-battery voltage will not inadvertently be passed through the filament.

Means for mounting the valve on the base or panel-board are provided, consisting of a plug 11 projecting from the lower surface of the base portion 5 and preferably carried unitarily therewith in any suitable manner. In Fig. 3 the plug is embedded directly into the insulating material of the base as is indicated at 12. The plug is preferably tapered and may be introduced directly into a correspondingly tapered socket 14 formed in the instrument-board. The plug 11 is preferably made from elastic material such as rubber, of non-microphonic character so that vibrations from the instrument-board will not be communicated to the valve. It is, however, within the spirit of the invention to form the plug from any other suitable resilient substance.

While I have in the above description disclosed what I believe to be a preferred and practical embodiment of my invention, it is to be understood that the specific details described are not limitative in their effect upon the invention but merely illustrative except in so far as they are expressly prescribed by the terms of the appended claims.

Having described my invention what I claim as new and desire to secure by Letters Patent, is:—

1. A thermionic valve including a base portion, lateral terminals carried by said base portion, and an elastic plug projecting from the lower face of said base portion and overhung by the latter, said plug being designed for direct insertion in a depression in a supporting member without the intervention of a terminal-carrying socket.

2. A thermionic valve including a base portion, terminals carried by said base portion, and an elastic plug projecting from the lower face of said base portion and designed for direct insertion in a depression in a supporting member without the intervention of a terminal-carrying socket.

In testimony whereof I have hereunto set my hand.

ROBERT L. COONEY.
